DESIGN FOR A GAME BOARD

Clifford E. Vanek, Cleveland, Ohio

Application September 27, 1941, Serial No. 103,538

Term of patent 14 years

To all whom it may concern:

Be it known that I, Clifford E. Vanek, a citizen of the United States and a resident of Cleveland, in the county of Cuyahoga and State of Ohio, have invented a new, original, and ornamental Design for Game Boards, of which the following is a specification, reference being had to the accompanying drawing, forming a part thereof.

The figure is a plan view of a game board, showing my new design. The article is of no appreciable or substantial thickness. The drawing is lined for contrasting colors.

I claim:

The ornamental design for a game board, substantially as shown and described.

CLIFFORD E. VANEK.
